(57) **CLAIM**

The ornamental design for a card case, as shown and described.

DESCRIPTION

FIG. 1.1 is a top perspective view of a card case in a folded configuration;

FIG. 1.2 is a bottom perspective view of the card case in the folded configuration;

FIG. 1.3 is a top perspective view of the card case in an unfolded configuration;

FIG. 1.4 is a bottom perspective view of the card case in the unfolded configuration;

FIG. 1.5 is a top view of the card case in the folded configuration;

FIG. 1.6 is a bottom view of the card case in the folded configuration;

FIG. 1.7 is a front view of the card case in the folded configuration;

FIG. 1.8 is a right, side view of the card case in the folded configuration;

FIG. 1.9 is a back view of the card case in the folded configuration; and

FIG. 1.10 is a left, side view of the card case in the folded configuration.

(Continued)

The broken lines are included for the purpose of illustrating environmental structure and forms no part of the claimed design.

1 Claim, 10 Drawing Sheets
